DESIGN FOR A COMBINATION AIR COMPRESSOR AND AIR FILTERS

John R. Folmer, Seattle, Wash.

Application April 30, 1940, Serial No. 92,040

Term of patent 14 years

To all whom it may concern:

Be it known that I, John R. Folmer, a citizen of the United States and a resident of Seattle, in the county of King, State of Washington, have invented a new, original, and ornamental Design for a Combination Air Compressor and Air Filters, of which the following is a specification, reference being had to the accompanying drawing, forming a part thereof.

Figure 1 is a perspective view of a combination

air compressor and air filters showing my new design.

Figure 2 is a front elevational view of the device shown in Figure 1.

Figure 3 is a top plan view of the device shown in Figure 1.

I claim:

The ornamental design for a combination air compressor and air filters, substantially as shown.

JOHN R. FOLMER.
